UNITED STATES PATENT OFFICE.

DUNCAN ROBINSON, OF BOSTON, MASSACHUSETTS.

VENTILATOR.

SPECIFICATION forming part of Letters Patent No. 774,277, dated November 8, 1904.

Application filed March 28, 1904. Serial No. 200,237. (No model.)

To all whom it may concern:

Be it known that I, DUNCAN ROBINSON, of Boston, county of Suffolk, State of Massachusetts, have invented an Improvement in Ventilators, of which the following description, in connection with the accompanying drawings, is a specification, like characters on the drawings representing like parts.

This invention relates to ventilators, and is intended to improve the construction of the ventilator to the end that it may be easily and cheaply manufactured.

The ventilator comprises, essentially, a hollow spherical body having oppositely-disposed side openings, preferably circular in shape, a pipe to which said body is attached which projects up into said body, and weather guards or shields, also preferably circular in shape, suitably supported in front of said side openings, but sufficiently removed therefrom to provide ample exit-passages between the guards or shields and the spherical body.

Figure 1 shows in front elevation a ventilator embodying this invention. Fig. 2 is a side elevation of the ventilator shown in Fig. 1, and Fig. 3 is a vertical section of the ventilator shown in Fig. 1.

a represents a hollow spherical body, and *b* a pipe to which it is attached, said pipe projecting up into said body, as shown in Fig. 3. The spherical body is preferably integrally formed. The spherical body may be provided with a flange *a'*, which embraces the pipe, and rivets may be employed for securing the parts together which pass through said flange and pipe, or said body may be otherwise secured to said pipe. The hollow spherical body *a* has two oppositely-disposed side openings *a'' a''*, which are preferably made circular in shape, although not necessarily so, said openings serving as the exits from the spherical body, and, if desired, more than two openings may be provided. In front of each side opening *a''* a weather guard or shield *c* is supported at a suitable distance from the body to provide a passage for the escape of the smoke, foul air, &c.

The weather guards or shields *c* are preferably made circular in shape and as concavo-

convex disks—as, for instance, they may be struck up from sheet metal—yet said guards or shields may be of any other suitable shape, and as a means of supporting them in vertical planes in front of said side openings a cross-bar *d* passes diametrically through the hollow spherical body and through the pipe *b*, and said cross-bar projects from the opposite side openings *a''* suitable distances to receive upon its projecting ends the two guards or shields *c*. The cross-bar *d* is thus supported by the pipe. A sleeve *d'* is placed upon each end of said cross-bar, which abuts against the pipe, and the guards or shields *c* are then placed on the projecting ends of said cross-bar against the outer ends of said sleeves, and the outer ends of the cross-bar are screw-threaded to receive nuts, which when placed thereon and turned up tightly will engage the guards or shields *c* and hold them tightly in position against the outer ends of the sleeves. The guards or shields are thereby securely held in place, although in lieu of this particular means of supporting the guards or shields *c* any other suitable means may be provided.

At the bottom of the hollow spherical body one or more small apertures *a''* are provided for the escape of any water that may collect therein.

Having thus described my invention, what I claim as new, and desire to secure by Letters Patent, is—

1. In a ventilator, a hollow spherical body having oppositely-disposed circular side openings, a pipe to which it is attached, which projects up into said body, a cross-bar passing through said body, the ends of which project from the side openings thereof and circular concavo-convex weather guards or shields supported by said cross-bar in front of said side openings, but sufficiently removed therefrom to provide exit-passages, substantially as described.

2. In a ventilator, a hollow spherical body having oppositely-disposed side openings, a pipe to which it is attached which projects up into said body, a cross-bar passing diametrically through said body and through said pipe, the ends of which project from said side open-

2
ings, and weather guards or shields supported upon the projecting ends of said cross-bar, substantially as described.

3. In a ventilator, a hollow spherical body having oppositely-disposed side openings, a pipe to which it is attached which projects up into said body, a cross-bar passing diametrically through said body and through said pipe, the ends of which project from the side openings, sleeves placed on said cross-bar, weather guards or shields mounted on said cross-bar

which bear against said sleeves, and means for holding said shields in place on the cross-bar, substantially as described.

In testimony whereof I have signed my name ¹⁵ to this specification in the presence of two subscribing witnesses.

DUNCAN ROBINSON.
